NILS A. WAHLBERG, OF WILKINSBURG, PENNSYLVANIA, ASSIGNOR TO WESTINGHOUSE ELECTRIC & MANUFACTURING COMPANY, A CORPORATION OF PENNSYLVANIA

TRANSMISSION LINE DEVICE

Application filed August 29, 1927. Serial No. 216,145.

My invention relates to transmission-line devices, and particularly to electrostatic-field control devices for high-voltage insulators.

- 5 One object of my invention is to provide an electrostatic-field-controlling device for a high-voltage insulator that shall also function as means for holding or maintaining the insulator in position.
- 10 Another object of my invention is to provide an electrostatic-field-controlling device that shall facilitate its assembly and mounting in operative position.

15 A further object of my invention is to provide a transmission-line device of the above indicated character that shall be simple and durable in construction, economical to manufacture and effective in its operation.

20 In electrostatic-field-controlling devices, such as arcing-ring structures having ring portions of relatively great diameter and radial supporting arms, difficulties are encountered in suitably and economically connecting the outer ends of the supporting arms 25 to the ring portions, without interrupting the arc-assuming surfaces of the rings. Difficulties are also encountered in mounting the supporting arms on the insulator structure.

25 It is my aim to overcome the above mentioned difficulties and also, to provide an arcing-ring structure that, in addition to its usual function of controlling the electrostatic field about the insulator, shall, also, mechanically function to assist in holding 30 attaching parts of the insulator to each other.

Accordingly, in practicing my invention, I provide a field-control structure comprising a radially divided ring portion that is so constructed and related to a supporting 40 arm member therefore, and in which the supporting arm member is so related to attaching parts of the insulator as to provide an extremely simple and economical device that facilitates its assembly in mounting and assists in holding the attaching parts of the 45 insulator together.

Figure 1 of the accompanying drawing is a side elevational view of a transmission-line device embodying my invention, showing 50 only the upper unit of a series string of simi-

lar units with which the device is adapted to cooperate,

Fig. 2 is a top plan view of a portion of the structure shown in Fig. 1, with parts omitted for clearness,

Fig. 3 is a sectional view taken substantially along the line III—III of Fig. 1,

Fig. 4 is a sectional view taken along the line IV—IV of Fig. 3 and,

Fig. 5 is a detail view, similar to the upper 60 central portion of Fig. 1, of a modified form of my invention.

A suspension insulator of usual construction comprises a dielectric body member 2, a pin member 3 and a cap member 4 having a 65 socket portion 5 for the reception of a ball-end shank or other suitable link connector member 6 having a hook for attaching the insulator to a tower or other suitable support, as by a co-operating detachable connector element or eye 8. A cotter pin 9 may be provided to hold the ball of the member 6 in position.

An electrostatic-field-controlling device of 75 my invention comprises a supporting arm or element 10 of inverted substantially U shape, preferably constructed of flat sheet or strap metal having an apertured intermediate portion 12 for attachment to the member 6, and free end portions 14 for supporting an annular arc-assuming element 15.

The intermediate portion 12 may be securely positioned on the member 6, as by a bolt or screw 17 and suitable positioning 85 lugs 18.

Each free end portion 14 of the supporting member 10 is provided with oppositely projecting cylindrical portions 20 and 21, the portion 20 of which may be in the form of a cylindrically-headed bolt having a shank 90 portion 22 projecting through an opening in the end 14 for the reception of projection 21 in the form of a cylindrical nut. The projections 20 and 21 may, of course, be otherwise constituted and rigidly fixed to the free end 95 14, as by welding.

The ring or annular arc-assuming element 15 is preferably divided into sections or halves of tubular material, or solid material, 100 having apertured ends which telescopically

fit the projections 20 and 21 and are held in place, as by screws 24, extending through apertures in the halves of the element 15 and into tapped openings in the projections 20 and 21.

In the above described structure, after the hook of the member 6 has been placed in position in the eye member 8, mounting of the electrostatic-field-controlling device and placing of the screw 17 relative to the hook of the member 6, prevents displacement of the hook from the eye member 8.

Also, the mounting of the halves of the annular element 15 is rendered an exceedingly easy operation by fitting the ends thereof to the projections 20 and 21 and placing the screws 24 in position. This structure also, permits either half of the element 15 to be removed and replaced without disturbing or detaching the other element from the supporting member 10.

Further, by forming the element 10 of flat strap or sheet material, and the arc-assuming portion 15 of standard rod or tubing, the construction thereof is rendered exceedingly economical and effective.

In the form of my invention shown in Fig. 5, in which corresponding parts are designated by corresponding reference characters, the construction of the parts is substantially the same as in the above described structure, with the exception that the intermediate portion 12 of the supporting member 10 is disposed at a lower position on the hook of the member 6. By this construction, the portion 12 not only functions to prevent removal of the hook of the member 6 from the eye 8 but also, prevents displacement of the hook from the socket portion 5. In the latter case, to remove the hook from the socket, it is necessary to move the hook and socket toward each other, in order to remove the ball, at the lower end of the hook, laterally through the entrance to the socket. With the lower edge of the portion 12 properly positioned, the hook and socket cannot be moved to so permit their separation. Obviously the portion 12 may be constructed of slightly greater width to have its upper edge in a position corresponding to the upper edge thereof in Fig. 1 and its lower edge in the position thereof shown in Fig. 5.

While I have shown and described particular forms of my invention, changes may be effected therein without departing from the spirit and scope thereof, as set forth in the appended claims.

I claim as my invention:

1. A transmission-line device comprising the combination with an insulator including metal terminals, of an electrostatic-field-controlling device therefor comprising a supporting portion distinct from either of said terminals and an arc-assuming portion telescopically fitting said supporting portion.

2. A transmission-line device comprising the combination with an insulator, of an electrostatic-field-controlling device therefor comprising a supporting portion having a plurality of receiving portions and a plurality of arc-assuming portions telescopically fitting said receiving portions. 70

3. A transmission-line device comprising the combination with an insulator, of an electrostatic-field-controlling device therefor 75 comprising a supporting portion having a plurality of oppositely-extending receiving portions and a plurality of arc-assuming portions telescopically fitting said receiving portions. 80

4. A transmission-line device comprising the combination with an insulator, of an electrostatic-field-controlling device therefor comprising a radially-divided arc-assuming portion and a supporting arm having an 85 outer end portion telescopically fitting ends of said arc-assuming portion formed by the division thereof.

5. A transmission-line device comprising the combination with an insulator, of an 90 electrostatic-field-controlling device therefor comprising a supporting arm having an inner end supported adjacent to the insulator axis and oppositely-extending projections adjacent to its outer end, and a radially-split 95 annular arc-assuming element having apertured ends telescopically fitting said projections.

6. A transmission-line device comprising the combination with an insulator, of an 100 electrostatic-field-controlling device therefor comprising a supporting member of substantially U-shape having adjacent to each free end thereof, oppositely-extending cylindrical projections at substantially right angles 105 to the end and a halved annular tubular arc-assuming element, the ends of which telescope 110 said projections and are held in position thereon.

In testimony whereof, I have hereunto subscribed my name this 24th day of August, 1927.

NILS A. WAHLBERG.
